(57) **CLAIM**

We claim, the ornamental design for a floor cleaning system, as shown and described.

DESCRIPTION

FIG. 1 is a front perspective view of a first embodiment of the design;

FIG. 2 is a rear perspective view of the design of FIG. 1;

FIG. 3 is front view of the design of FIG. 1;

FIG. 4 is a rear view of the design of FIG. 1;

FIG. 5 is a first side view of the design of FIG. 1;

FIG. 6 is a second side view of the design of FIG. 1;

FIG. 7 is a top view of the design of FIG. 1;

FIG. 8 is a bottom view of the design of FIG. 1; and,

FIG. 9 is a bottom perspective view of the design of FIG. 1. References to “side”, “top”, “front”, “rear” and “bottom” in the figure descriptions are not meant to require certain in-use orientation; a floor cleaning system according to the claimed design may be used in any orientation.

The broken lines depict portions of the floor cleaning system in which the design is embodied that are not considered part of the claimed design.
